AUTOMATIC WATER SUPPLYING DEVICE FOR WET BATTERIES

William T. Schuster, Aurora, Colo.

Application March 18, 1955, Serial No. 35,106

Term of patent 14 years

(Cl. D26—6)

Figure 1 is an elevational view of an automatic water supplying device for wet batteries showing my new design;

Figure 2 is a top plan thereof;

Figure 3 is a bottom view; and

Figure 4 is a vertical cross sectional view thereof.

I claim:

The ornamental design for an automatic water supplying device for wet batteries, as shown.
